UNITED STATES PATENT OFFICE.

DANIEL E. THOMAS, OF TOLEDO, OHIO.

FILE FOR KEEPING RECORDS.

SPECIFICATION forming part of Letters Patent No. 518,380, dated April 17, 1894.

Application filed August 18, 1892. Serial No. 443,004. (No model.)

To all whom it may concern:

Be it known that I, DANIEL E. THOMAS, of Toledo, county of Lucas, and State of Ohio, have invented certain new and useful Im-

5 provements in Files for Keeping Records; and I do hereby declare that the following is a full, clear, and exact description of the invention, which will enable others skilled in the art to which it appertains to make and use 10 the same, reference being had to the accompanying drawings, and to the letters and figures of reference marked thereon, which form part of this specification.

My invention relates to a file for keeping 15 records, and has for its object to provide a plurality of record cards of novel arrangement, for coaction with a plurality of calendar cards, having notations for the days of the month, and a plurality of like cards having 20 notations for the months of the year.

The invention further consists in a file comprising record cards of novel arrangement, and calendar cards for days and months which coact with a gage card when assembled 25 in a file receptacle, whereby a correct record of business transactions present and prospective may be compactly kept.

The invention consists in the parts, and combination of parts, hereinafter described 30 and pointed out in the claims.

In the drawings: Figure 1 is a front elevation of a file receptacle, standing upon end, and supplied with a complete set of cards comprising a gage board calendar cards, and 35 indexed record cards. Fig. 2 is a plan view of a record card, showing the supplemental attachable index strip attached to the card in line with one of the letters. Fig. 3 is a perspective view of a file cabinet provided 40 with a plurality of file receptacles, this view being drawn on a smaller scale than the other two views.

My invention is particularly adaptable in 45 offices where matters as accounts, &c., received and entered one day will necessarily demand attention at subsequent periods.

1 designates a file box of a preferred construction comprising the bottom board 2, front end board 3, side boards 4, and top 50 board 5, and in order to properly assemble the business records of an office I provide a file cabinet 6 into which a number of file re-

ceptacles are placed, and properly labeled upon the front end whereby ready reference may be made to a file receptacle containing any particular date desired.

In carrying out the process of recording and indexing, I may employ what I term a gage 7 comprising a card or board having the letters of the alphabet arranged upon the same, preferably upon each outer edge thirteen letters upon each side, this gage being placed upon the top of the file, as I shall hereinafter designate the cards when assembled.

8 designates a record card either plain or 65 provided with the letters of the alphabet, preferably arranged with thirteen letters upon each side as shown. The arrangement of the letters however, upon the record card is unnecessary, when the gage board is employed.

9 designates calendar cards, the body of which are preferably of the same size of the gage board and record cards, with an upper portion 10 extending slightly above the record cards, in order to disclose the numerals thereon, which designate each day of the month, that is, there is a calendar card for each day of the month, one of each of the cards having a numeral upon the upper projecting portion to designate a day of the month, and there is also a set of calendar cards in rear of the cards which designate the days, formed substantially like the same, upon the projecting portion of which is noted the 85 months of the year.

11 designates an attachable strip or tab, upon which is placed the index letters, the tab being preferably formed blank, and with an adhesive inner end by which to secure the same to the record card.

In operation, we will suppose the letters to be omitted from the record card, as shown in the first two cards in Fig. 1, and that a record of account has been noted upon a record 95 card which records the fact that Brown has a debit account payable on the eighteenth of the month, a tab is secured to the record card, and the letters "Bro." written upon the tab when the card is placed just upon the calendar card having the numeral 18, and so in like manner other record cards are filled out with notations of matter demanding attention at a future date and the tab properly indexed

affixed to the margin with the initial letter in alignment with the same particular letter on the gage board, the latter always insuring this proper alignment, and also tending to hold 5 the several cards in position, as I prefer to make this card of greater weight than the others. It will be seen that no matter where a record card may be placed among the calendar cards in the file in order to bring it to attention at a desired date, the tab upon each 10 card will always be in alignment with the letter upon the gage card, which is initial to the name upon the record card, and the latter can be easily found by running down the proper 15 row of tabs and observing the letters thereon.

I may dispense with letters on the gage board, and print the letters of the alphabet upon each record card if desired, as shown in the third and fourth cards in Fig. 1 in 20 which event, the letters serve as a gage by which to secure the indexing tab to the record cards in perfect alignment. I also form the tab of sufficient size to allow of more than one letter, as, for instance, if the record of 25 matter pertains to Brown I may note on the tab "Bro."

The file receptacles are assembled in the cabinet by being labeled with the second, and, if necessary, succeeding letters of the 30 names upon the record cards contained by them. To illustrate, a record card with the name of Brown will be found in the file receptacle labeled R. Should there be more record cards with R for second letter than 35 one file receptacle will hold, two or more may be provided and the record cards distributed among them by a division of the third letter, for instance, if two R receptacles are provided they may be labeled RA to RL and RM to 40 RZ respectively, in which case all names without regard to initial letters, in which the second letter is R and the third is any letter from A to L inclusive will be in the first R receptacle, and those in which the third letter is any letter from M to Z will be in the 45 second R receptacle. It is therefore seen that the file receptacles labeled by the second and succeeding letters of the names recorded, in combination with the record cards which they 50 contain, indexed by the initial letters of such names, constitute a single index system.

In use, each day, the calendar card for that day is transferred to the rear of the other day calendar cards as soon as that day's business

is disposed of. This brings to the top of the 55 file the record cards which have been placed upon the calendar card of the succeeding day.

To dispose of the business of a day, each file receptacle is examined, and the record card or cards appearing upon the particular 60 calendar card of that day are disposed of, and when the business upon a record card is completed the card is removed, thereby dispensing with the necessity of mixing accounts with those already disposed of, as in the present 65 system of bookkeeping.

The monthly cards are for the purpose of arranging the record cards that only demand attention in some month subsequent to the term embraced by day calendar cards, as for 70 instance, if the account of Brown received on the tenth of a current month, as August, and demands attention the 10th of October, the record card is placed upon the October card, and each month the monthly cards are examined, so that when October becomes the 75 current month, the card of Brown is placed upon the calendar card bearing the date "Tenth."

It will be seen that the gage board is 80 convenient if used to align the tabs, and also as a weight to hold the cards assembled, as well as a support against which the cards may rest when being examined.

What I claim is—

1. An improved record file, comprising a 85 holder, a series of calendar cards properly arranged, a series of record cards arranged between the calendar cards, and a gage board having the letters marked upon its margin for the purpose set forth.

2. An improved record file comprising in 90 combination a holder, a series of calendar cards properly arranged, a series of record cards arranged between the calendar cards, each record card having its margin marked 95 to indicate the point of attachment of an index tab, and a gage board having the letters marked upon its margin for the purpose set forth.

In testimony that I claim the foregoing as my own I hereby affix my signature in presence of two witnesses.

DANIEL E. THOMAS.
